WHISTLE FOR TOY RAILWAYS

Melvin R. Hall, Atlantic City, N. J.

Application February 14, 1936, Serial No. 63,889

12 Claims. (Cl. 46—202)

This invention relates to a whistle for toy railways.

The invention is intended for specific application to toy electric railways and especially where it is desired to employ signaling means, for example, simulating the whistle of a locomotive.

It is an object of my present invention to provide an extremely simple and highly effective device which may be easily built into the usual electric toy locomotives without a great deal of additional expense to the consumer.

Another object of this invention is to provide a toy of the type described in which the motor for driving the fan runs continuously, novel means being provided for merely interrupting the air passage of the whistle as to render it audible.

A further object of the invention is to provide timing means associated with the whistle as to cause it to signal at various intervals, for example, two long blasts, and a pair of short ones immediately following, each signaling operation or rather cycles of operation being automatically controlled by either the distance covered by the toy vehicle or at regular intervals of time instead of distance.

It is still a further object of my invention to associate the continuously rotatable fan blower and whistle sounding means to be actuated by means of remote control.

Other objects of this invention will herein-after be set forth, or will be apparent from the description and the drawing, in which is illustrated an embodiment of apparatus for carrying out the invention.

The invention, however, is not intended to be restricted to any particular construction or arrangement of parts, or to any particular application of such construction, or to any specific manner of use, or to any of various details thereof, herein shown and described, as the same may be modified in various particulars or be applied in many varied relations without departing from the spirit and scope of the claimed invention, the practical embodiment herein illustrated and described merely being one of various forms and modifications in which the invention might be embodied.

On the drawing, in which the same reference characters refer to the same parts throughout, and in which is disclosed such embodiments:

Figure 1 is a side view of a toy electric locomotive, the invention diagrammatically illustrated in dotted lines;

Figure 2 is a view in side elevation of my invention;

Figure 3 is a similar view partially broken away, illustrating the assembly from the opposite side;

Figure 4 is a front view of the whistle portion as illustrated in Figure 3, parts being broken away for clearness;

Figure 5 is a top plan view of the assembly shown in Figure 3, a portion of the casing thereof being broken away and shown in section, and

Figure 6 is a fragmentary side elevation, parts thereof omitted, of another embodiment of my invention.

My invention, in the forms or embodiments shown in the drawing, and briefly described comprises a motor 10 which is adapted to continuously rotate the fan blower 11 during the operation of the toy train, a whistle 12, a movably mounted member 13 for controlling the signaling and timing means indicated generally as at 14.

The toy locomotive is of the usual type well known in the art and is indicated at 15 and is, of course, provided with the usual drive wheels 16 which are driven by gearing from the motor 17.

In the embodiment of my invention illustrated in Figures 1, 2 and 5 inclusive is shown the timing means 14 as being controlled from the driving gear of the locomotive, that is to say, the signaling means will be operated in direct proportion to the distance covered by the train. In this arrangement I may employ a self-contained frame indicated at 18 for housing the novel features of my invention in the form of a single unit.

The fan blower 11 is provided with a rotor 19 having suitably arranged blades 20 which is journaled in bearings formed in the side walls of the frame work 18. A pulley 21 is secured upon one end of the rotor shaft 22 for the purpose of receiving the belt 23.

The motor for continuously driving the fan blower 11 is indicated at 24 and may be of the same type as is usually employed in this class of toys. The pulley 25 is secured upon the motor shaft 26 and is likewise grooved as the pulley 21 for receiving the belt 23. The fan blower 11 is provided with an outwardly extending and substantially tubular portion 27 which is closed at the end as shown at 28. An opening or passageway 29 is formed transversely across the outer face of the tubular portion 27 and is suitably located as to provide the desired pitch to the whistle, simulating as near as possible the signaling device of a locomotive.

The timing means indicated generally as at 14 consists of a train of gears for rotating the cam or toothed disc 30 for the purpose which be readily seen. Meshing with the gear wheel 31 which is the usual gear for driving the wheels 16 is a relatively small idler gear 32 suitably supported upon a bracket 33 carried by the fan blower 11. This gear 32, it will be noted, meshes with the gear 34 upon which is mounted the 10 smaller gear 35 for driving the larger gear 36. The gear 36, it will be appreciated, is carried upon the shaft 37 which likewise supports the mitre gear 38 for the purpose of driving the similarly formed gear 39. The mitre gear 38 is 15 secured to one end of the shaft 40 which is supported by the bearings 41 and 42 upon the shaft 40. On the end opposite from the gear 39 is secured a worm 43 and is adapted to mesh with the toothed portion 44 of the toothed disc 30.

20 The teeth or lugs shown at 45 and 46 may be formed on the inner side of the worm gear 30 in any usual manner, and are so arranged as to simulate two long blasts and two short blasts of a train whistle. Obviously, other arrangements or numbers of teeth may be employed.

An arm 50 is pivotally mounted at 51 to the side wall of the frame work substantially midway the length thereof for the purpose of actuating the signaling means from the toothed disc or 30 worm gear 30. The end 52 of this arm 50, it will be noted is in the path of movement of the lugs or teeth 45 and 46 whereas the opposite end 53 thereof is provided with an arm which is adapted to engage the transversely arranged 35 opening 29. A coil spring 54 may be employed for maintaining the arm 50 in a position which renders the whistle inaudible.

A switch 55 may be employed for silencing means if desired.

40 In the embodiment of my invention shown in Figure 6, the timing disc 14 which is in the form of a peripherally toothed disc 59 is driven by means of a pair of worm gears directly from the fan blower shaft 22. A vertically slideable rod 56 is provided with an off-set arm portion 57 which is adapted to overlie the transversely extending air escape passage 29. The lower end of this rod 56, it will be noted, is provided with a flanged roller 58 and is in constant contact with the periphery of the toothed disc 59 by means of the coil spring 60.

From the foregoing description it will be readily understood that the whistle is blown at predetermined cycles which are directly proportional with 55 either the distance covered by the toy train as when the timing mechanism is controlled by the train motor, or between regular intervals of time if the timing mechanism is driven from the fan blower. It may be here stated that should it be 60 found desirable to cause the blowing of the whistle by means of remote control instead of automatically, as above described, I may employ a small D. C. coil in the toy train and energize or deenergize it by means of a hand operated 65 momentary-snap switch. Obviously, in this arrangement also, the arm which overlies the transversely extending air-escape passage is caused to move from and to this passage to effect the blowing or silencing of the whistle. It is to be 70 understood that I may eliminate the timing mechanism and control the blowing and the silencing of the whistle directly from the snap switch. Since the fan blower is continuously operated, it not being required to start and stop 75 the fan motor each time the child wishes to blow

the whistle or silence it, I have obtained excellent results with both of the above-mentioned embodiments of my invention.

Many other changes could be effected in the 5 particular apparatus designed, and in the methods of operation and use set forth, and in specific details thereof, without substantially departing from the invention intended to be defined in the claims, the specific description herein being of 10 an illustrative operative embodiment capable of carrying out the spirit of the invention.

What is claimed as new and useful is:—

1. In combination with a toy vehicle having drive wheels and a motor for imparting rotation thereto, a signalling device comprising a motor independent from the first named motor, a fan blower connected with the second named motor and arranged to drive the fan blower continuously during the operation of the toy vehicle, a whistle in communication with the fan blower, 15 and a movably mounted member associated with the whistle for either obstructing the flow of air therethrough rendering said whistle inaudible, or releasing the flow of air between the fan blower and said whistle effecting the audible signaling thereof. 20

2. In combination with a toy vehicle having drive wheels and a motor for imparting rotation thereto, a signalling device comprising a motor independent from the first named motor, a fan 30 blower connected with the second named motor and arranged to drive the fan blower continuously during the operation of the toy vehicle, a whistle in communication with the fan blower, a movably mounted member associated with the whistle for either obstructing the flow of air therethrough rendering said whistle inaudible, or releasing the flow of air between the fan blower and said whistle effecting the audible signaling thereof, and operating means for said 35 movably mounted member. 40

3. In combination with a toy vehicle having drive wheels and a motor for imparting rotation thereto, a signalling device comprising a motor independent from the first named motor, a fan 45 blower connected with the second named motor and arranged to drive the fan blower continuously during the operation of the toy vehicle, a whistle in communication with the fan blower, and a movably mounted member associated with the 50 whistle for either obstructing the flow of air therethrough rendering said whistle inaudible, or releasing the flow of air between the fan blower and said whistle effecting the audible signaling thereof, said whistle having a transversely extending air-escape passage. 55

4. In combination with a toy vehicle having drive wheels and a motor for imparting rotation thereto, a signalling device comprising a motor independent from the first named motor, a fan 60 blower connected with the second named motor and arranged to drive the fan blower continuously during the operation of the toy vehicle, a whistle having a transversely extending air-escape passage, said whistle being operable from the fan blower, a movable member having an arm arranged to overlie said transverse air-escape passage for either obstructing the flow of air therethrough rendering said whistle inaudible, or releasing the flow of air between the fan 65 blower and said whistle effecting the audible signaling thereof. 70

5. In combination, a toy vehicle having drive wheels and a motor for imparting rotation thereto, a signalling device comprising a motor inde- 75

- pendent from the first named motor, a fan blower connected with the second named motor and arranged to drive the fan blower continuously during the operation of the toy vehicle, a whistle 5 having a transversely extending air-escape passage, said whistle being operable from the fan blower, a movable member having an arm arranged to overlie said transverse air-escape passage for either obstructing the flow of air 10 therethrough rendering said whistle inaudible, or releasing the flow of air between the fan blower and said whistle effecting the audible signaling thereof, and operating means for said movably mounted member.
- 15 6. In combination, a toy vehicle having drive wheels and a motor for imparting rotation thereto, a signaling device comprising a motor independent from the first named motor, a fan blower having a substantially tubular portion extending 20 outwardly from the periphery of said fan blower, the extreme end of the tubular portion being closed, said tubular portion being further provided with a transversely extended air-escape opening, and a movably mounted member associated with the transversely extending opening for either obstructing the flow of air therethrough rendering said whistle inaudible, or releasing the flow of air between the fan blower and said whistle effecting the audible signaling 25 thereof, and said fan blower being connected with the second named motor and arranged to drive the fan blower continuously during the operation of the toy vehicle.
7. A toy vehicle, drive wheels and a motor for 30 imparting rotation thereto, a signaling device comprising a motor independent from the first named motor, a fan blower having a substantially tubular portion extending outwardly from the periphery of said fan blower, the extreme end 35 of the tubular portion being closed, said tubular portion being further provided with a transversely extending air-escape opening, a movably mounted member associated with the transversely extending opening for either obstructing 40 the flow of air therethrough rendering said whistle inaudible, or releasing the flow of air between the fan blower and said whistle effecting the audible signaling thereof, and operating means for said movably mounted member, said 45 fan blower being connected with the second named motor and arranged to drive the fan blower continuously during the operation of the toy vehicle.
8. A signaling device for toy vehicles comprising 50 a revolvably mounted fan blower, means for rotating said fan blower, a whistle, a tubular connecting portion extending between the fan 55 blower and said whistle, a movably mounted member placed in the path of the opening of the whistle for obstructing the flow of air therethrough rendering said whistle inaudible, said movable member adapted to be moved from the path of said opening to effect the audible signaling of the whistle, and means for operating said movably mounted member.
9. A signaling device for toy vehicles comprising 60 a revolvably mounted fan blower, a motor for continuously rotating said fan blower, a whistle, a tubular connecting portion extending between the fan blower and said whistle, a movably mounted member placed in the path of the opening of the whistle for obstructing the flow of air therethrough rendering said whistle inaudible, said movable member adapted to be moved from the path of said opening to effect the audible signaling of the whistle, and means for operating said movably mounted member.
10. In combination, a toy vehicle having drive 65 wheels and a motor for imparting rotation thereto, a signaling device comprising a fan blower, a motor independent of the first-named motor for continuously driving said fan blower, a 70 whistle in communication with said fan blower and self-contained timing means carried by said toy vehicle for actuating the whistle at predetermined intervals.
11. In combination with a toy vehicle having 75 drive wheels and a motor for imparting rotation thereto, a signaling device comprising a motor independent of the first-named motor, a fan blower connected with the second-named motor and arranged to drive the fan blower continuously 80 during the operation of the toy vehicle, a whistle in communication with the fan blower, said whistle having a transverse opening therein, a movable member adapted to align with said transverse opening, and timing means operable 85 by the movement of said vehicle for actuating said movable member.
12. In combination with a toy vehicle having 90 drive wheels and a motor for imparting rotation thereto, a signaling device comprising a motor independent of the first-named motor, a fan blower connected with the second-named motor and arranged to drive the fan blower continuously 95 during the operation of the toy vehicle, a whistle in communication with the fan blower, said whistle having a transverse opening therein, a movable member adapted to align with said transverse opening, and timing means operable 100 by the movement of said vehicle for actuating said movable member, said timing means driven from the fan blower.

MELVIN R. HALL.
